[57] CLAIM

The ornamental design for an autosound installation mounting device, as shown and described.

DESCRIPTION

FIG. 1 is a right, front perspective view of an autosound installation mounting device showing our new design;

FIG. 2 is a front elevation view of FIG. 1;

FIG. 3 is a top plan view of FIG. 1;

FIG. 4 is a right side elevation view of FIG. 1, the left side being a mirror image thereof;

FIG. 5 is a right side elevation in cross-section, along line 5—5 of FIG. 2, to better illustrate certain features of the disclosed design;

FIG. 6 is a bottom plan view of FIG. 1; and,

FIG. 7 is a rear elevation view of FIG. 1.

The broken line showing of a vehicle dashboard mounting structure on FIGS. 1 and 3 through 7 is for illustrative purposes only and forms no part of the claimed design.
